UNITED STATES PATENT OFFICE.

JOHN JAMES DILLON, OF WEST EDMONTON, ALBERTA, CANADA.

ATTACHMENT TO SWITCH-STANDS.

1,206,681.

Specification of Letters Patent. Patented Nov. 28, 1916.

Application filed December 20, 1915. Serial No. 67,848.

To all whom it may concern:

Be it known that I, JOHN JAMES DILLON, of the village of West Edmonton, in the Province of Alberta, Canada, have invented 5 certain new and useful Improvements in Attachments to Switch-Stands, of which the following is the specification.

The invention relates to improvements in attachments to switch stands, and the object 10 of the invention is to provide an attachment to the switch stand lever which will of itself operate automatically to hold the lever in the down position while accommodating the various depth notches appearing in the switch 15 stand table and which, further, is arranged so that the switchman can quickly release the lock to raise the lever when desiring to manipulate the switch.

With the above objects in view the invention consists essentially in a head piece secured to the switch stand crank shaft and provided with a slot, an operating lever secured to a cross pin pivotally mounted in the head piece and having the upper end thereof provided with an eye protruding through the slot and the rear side thereof fitted with ratchet teeth, a trip arm permanently secured to the pin, a latch pivotally secured to the head piece and operating on the arm, a 20 second cross pin pivotally mounted in the head and carried by the extending end thereof, a dog secured to the latter cross pin, housed within the head and engageable with the ratchet teeth, a trip bar secured to the latter cross pin and provided with an outstanding stud and a weight pivotally mounted on the latter pin and coöoperating with the stud and the latch, the parts being 25 arranged and constructed as hereinafter 30 more particularly described and later pointed out in the appended claims, reference being had to the accompanying drawing in which;

Figure 1 represents a side view of the attachment, as applied on a switch stand, with 35 the lever down, the switch stand being shown in vertical section. Fig. 2 represents a plan view of the attachment as applied on a switch stand. Fig. 3 represents a side view of the attachment with the lever swung 40 fully up. Fig. 4 is a longitudinal sectional view of the attachment with the parts in position as shown in Fig. 3. Fig. 5 is a vertical sectional view through the head, the

section being taken in the plane denoted by the line X—X' Fig. 1. Fig. 6 is a side view 55 of the parts as they appear in an intermediate position of the operating lever.

In the drawing like characters of reference indicate corresponding parts in each figure. 60

1 represents a switch stand of which 2 is a hollow standard connecting the base 3 with the table 4. The base is mounted in any suitable way on the ground and the table is supplied with a pair of notches 5 and 6. 65

7 represents the switch stand crank shaft which is rotatably mounted in the table and the base piece and to the crank of which is connected the usual switch bar 8.

The above parts are of ordinary construction and form no part of my invention. 70

My attachment is applied on the shaft 7 adjacent the table, and is now described in detail. It comprises a head piece 9 having one end fastened permanently by means of a 75 key 10 to the shaft 7 and arranged to operate over the table with the free end thereof overhanging the back edge of the table, which it will be noticed is concentric to the shaft and has the notches thereof spaced 80 apart ninety degrees. The free end of the head piece is constructed to present a housing 11 for certain parts later described, and it is provided with a slot 12 at the top, for a purpose later described. 85

13 is a cross pin passing across the housing and having the ends thereof rotatably mounted in the sides of the head piece, such pin being located directly beneath the slot.

14 is an operating lever having the upper 90 end thereof entering the housing and permanently secured to the pin 13. The upper end of the lever projects, in the down position of the lever, through the slot and is provided with an eye 15, while the rear face thereof 95 is fitted with a series of ratchet teeth 16 on which a dog 17 is designed to operate, the dog being normally contained within the housing and being fastened permanently to a second cross pin 18 pivotally mounted in 100 the sides of the head piece.

19 is a trip bar permanently secured to the cross pin 18 and fitted with an outstanding stud 20.

21 is a weight pivotally mounted on the 105 outer end of the pin 18 and adjacent the

trip bar. This weight is supplied with a notch 21' designed to receive the stud 20, and is fitted with a projecting lug 21².

The arrangement of the latter parts is

- 5 such that when the lever is down the weight operates on the stud to throw the dog in against the teeth on the operating lever, in which position it is shown in Fig. 1 of the drawing. According to this it is obvious
10 that when the lever is down it is automatically held locked by the action of the weight.

22 is a horizontally disposed trip arm permanently secured to the projecting end of the pin 13, on which it turns.

- 15 23 is a latch pivotally secured to the side of the head piece, as shown at 24, and having the free end thereof resting normally on the upper edge of the trip arm. The latch is supplied with an outstanding catch
20 25, arranged to catch the weight when the same is thrown over to release the dog.

A padlock 26 is supplied to lock the lever so that it cannot be manipulated without undoing the padlock with a key. The padlock 25 is attached to the eye 15 when the lever is in the down position, and prevents the movement of the lever as the head piece is fitted with an enlargement 9' to catch the padlock.

- 30 In order that the device may be better understood, I will now describe its operation, assuming initially, that the parts are in the position as shown in Fig. 1 of the drawing. When a switchman desires to manipulate the switch rail (not shown, but attached to the bar 8), he first removes the padlock and then swings the weight over by hand until it strikes and rests on the catch 25. As the weight turns over, the lug 21² is 40 designed to hit the stud and cause the stud to swing the trip bar and consequently effect the outward swinging of the dog clear of the teeth of the lever. The operating lever can then be swung upwardly and as it 45 swings up it turns the trip arm which raises the latch and causes the weight to be swung back until it is caught by the stud. It is here explained that the weight is caught by the stud before the lever reaches the horizontal position, (as shown in Fig. 3 of the drawing), and that although the weight, in this position, would cause the dog to swing in against the lever, still the dog does not at this time catch on the lever as it engages with said lever at a point where there are no teeth. For convenience in understanding this particular part of the action, the parts have been shown in Fig. 6, in the position they occupy when the lever is part way up and the dog is traveling on the smooth face of the lever. When the lever has been brought finally to the upper position, the shaft 7 can be turned to throw the weight as desired. The lever is then released and it drops of itself, by gravity, into the presented

slot. As it drops the weight swings back to the initial position with the result that the dog travels up the teeth and locks the lever in that final position.

From the above it is obvious that the lever is at all times positively locked against outward swing from the notch in which it has entered, and that a very convenient means is provided for initially releasing the lever, when it is desired to swing it upwardly, and for automatically locking the lever after the head has been manipulated and the switch brought to the desired position. It is explained that a series of ratchet teeth are provided so that the attachment 80 can be applied on various types of switch stands which very often have the notches of different depth.

What I claim as my invention is:—

1. The combination with a switch stand, 85 the crank shaft and the table thereof, having suitably disposed side notches therein, of a head piece permanently secured to the crank shaft and operating over the table, a downwardly extending pivoted operating 90 lever secured to the head piece and normally entering one of the notches, said lever having the rear face thereof fitted with a series of ratchet teeth, and a releasable dog pivotally secured to the head piece and normally 95 engaging with the teeth of the lever and holding the lever normally in closed position within the notch.

2. The combination with a switch stand, 100 the crank shaft and the table thereof, having suitably disposed side notches therein, of a head piece permanently secured to the crank shaft and operating over the table, a downwardly extending pivoted operating lever secured to the head piece and normally 105 entering one of the notches, said lever having the rear face thereof fitted with a series of ratchet teeth, a dog pivotally secured to the head piece and gravity operated means 110 for retaining the dog normally in engagement with the teeth of the lever to hold the lever in the down position.

3. The combination with a switch stand, 115 the crank shaft and the table thereof, having suitably disposed side notches therein, 120 of a head piece permanently secured to the crank shaft and operating over the table, a downwardly extending pivoted operating lever secured to the head piece and normally entering one of the notches, said lever having the rear face thereof fitted with a series of ratchet teeth, a cross pin rotatably mounted in the head, a dog housed within the head and secured to the cross pin and designed to operate on the teeth of the lever, a trip bar permanently secured to the cross pin, a stud extending from the bar and a weight pivotally mounted on the cross pin and engaging with the stud and designed 125 to effect, through the trip bar, the holding 130

of the dog normally against the teeth of the lever.

4. The combination with a switch stand, the crank shaft and the table thereof, having suitably disposed side notches therein, of a head piece permanently secured to the crank shaft and operating over the table, a downwardly extending pivoted operating lever secured to the head piece and normally entering one of the notches, said lever having the rear face thereof fitted with a series of ratchet teeth, a cross pin rotatably mounted in the head, a dog housed within the head and secured to the cross pin and designed to operate on the teeth of the lever, a trip bar permanently secured to the cross pin, a stud extending from the bar and a weight mounted on the cross pin and provided with a slot normally receiving the stud and with a lug designed to engage the stud in the swinging of the weight.

5. The combination with a switch stand, the crank shaft and the table thereof, having suitably disposed side notches therein, of a head piece operating over the table and permanently secured to the upper end of the crank shaft, a cross pin pivotally mounted in the extending end of the head, an operating lever secured to the pin and having the upper end thereof housed within the head and fitted on the rear side with a series of ratchet teeth and with the forward side normally entering one of the notches in the table, a second cross pin rotatably mounted in the head, a dog secured to the latter pin, a trip bar secured to the latter pin, a stud projecting outwardly from the bar, a weight pivotally mounted on the latter pin and provided with a slot normally receiving the stud and with a projecting lug, said weight being designed, with the stud in the slot, to hold the dog engaged with the ratchet teeth of the lever and when turned on the pin to effect, through the lug, the swinging of the stud and the release of the dog from the teeth, means carried by the head for catching the weight, when swung upwardly, to release the dog and means actuated by the lever in swinging outwardly to raise the catch and receive the weight.

Copies of this patent may be obtained for five cents each, by addressing the "Commissioner of Patents, Washington, D. C."

stud and the release of the dog from the teeth, a trip arm permanently secured to the former cross pin and a latch pivotally secured to the head and bearing normally on the arm and provided with a catch to receive the weight in the final upswung position thereof.

6. The combination with a switch stand, the crank shaft and the table thereof, having suitably disposed side notches therein, of a head piece operating over the table and permanently secured to the upper end of the crank shaft, a cross pin pivotally mounted in the extending end of the head, an operating lever secured to the pin and having the upper end thereof housed within the head and fitted on the rear side with a series of ratchet teeth and with the forward side normally entering one of the notches in the table, a second cross pin rotatably mounted in the head, a dog secured to the latter pin, a trip bar secured to the latter pin, a stud projecting outwardly from the bar, a weight pivotally mounted on the latter pin and provided with a slot normally receiving the stud and with a projecting lug, said weight being designed, with the stud in the slot, to hold the dog engaged with the ratchet teeth of the lever and when turned on the pin to effect, through the lug, the swinging of the stud and the release of the dog from the teeth, means carried by the head for catching the weight, when swung upwardly, to release the dog and means actuated by the lever in swinging outwardly to raise the catch and receive the weight.

Signed at Edmonton this 4th day of October, 1915.

JOHN JAMES DILLON.
